Primary Examiner — Kelley Donnelly(74) *Attorney, Agent, or Firm* — Alan G. Towner(57) **CLAIM**

The ornamental design for a display case, as shown and described.

DESCRIPTION

FIG. 1 is an isometric view of a display case showing our new design;

FIG. 2 is a front view thereof;

FIG. 3 is a back view thereof;

FIG. 4 is a right side view thereof;

FIG. 5 is a left view thereof;

FIG. 6 is a top view thereof;

FIG. 7 is a bottom view thereof; and,

FIG. 8 is an isometric view thereof including pouches placed in the display case.

The broken lines depict portions of the display case in which the design is embodied and form no part of the claimed design.
